UNITED STATES PATENT OFFICE.

CHARLES BOSWORTH, OF BROOKLYN, NEW YORK.

DESIGN FOR A PICTURE-FRAME MOLDING, &c.

SPECIFICATION forming part of Design No. 26,702, dated March 2, 1897.

Application filed January 11, 1897. Serial No. 618,884. Term of patent 3½ years.

To all whom it may concern:

Be it known that I, CHARLES BOSWORTH, a citizen of the United States, residing at the city of Brooklyn, county of Kings, and State of New York, have invented and produced a certain new and useful Design for Picture-Frame Moldings or the Like, of which the following is a specification.

My design consists in the configuration of a frame and in the separate moldings thereon.

In the drawings forming part of this specification, Figure 1 is a plan view of a section of a picture-frame embodying my design; and Fig. 2, a transverse sectional elevation through a corner of the frame, taken substantially on the plane of the line $\alpha\alpha$, Fig. 1.

In plan my design discloses three separate moldings 1, 2, and 3, the center one 2 being raised above the outer and inner moldings, as clearly shown in Fig. 2, the outer molding 1 consisting in a series of raised foliated figures 4 and 5, the center figure 4 being the largest, all of the figures being raised from a substantially plain and flat ground having a stippled surface. The inner molding 3 consists of a series of foliated figures 6, with interposed semielliptical panels 7, raised from a stippled base 8. The central or main mold-

ing 2 consists in a series of foliated figures 9, shell-like in appearance, with interspersed scroll-like figures 10 and panel figures 11, the corner figure 12 being apexed, as shown, with a central panel-like configuration 13.

As shown in the drawings, the three separate moldings are disposed at varying heights, the outer one 1 being the lowest in elevation, the inner one 3 the next highest, and the central or main molding 2 highest and most prominent.

Instead of disposing the moldings in straight parallel lines about a rectangular figure they may be produced upon a frame of oval or other design, the separate moldings then being concentric and the individual designs for the moldings can be separately used.

Having described my invention, I claim—

The design for a molding for a picture-frame, or the like, substantially as herein shown and described.

Signed at the city of Brooklyn, county of Kings, State of New York, this 6th day of January, 1897.

CHARLES BOSWORTH.
